Specification for Design.

Patented Nov. 25, 1913.

Application filed March 3, 1913. Serial No. 751,817. Term of patent 3½ years.

To all whom it may concern:

Be it known that I, FRANK M. LAYTON, a citizen of the United States, residing at Port Dickinson, in the county of Broome and State of New York, have invented a new, original, and ornamental Design for Floor-Scrapers, of which the following is a specification, reference being had to the accompanying drawings, forming a part thereof.

In the accompanying drawing a side view

of the new design of the scraper is shown in Figure 1 and an end view in Fig. 2.

I claim:

The ornamental design for a floor scraper, as shown.

In testimony whereof I have affixed my signature in presence of two witnesses.

FRANK M. LAYTON.
